Primary Examiner — Kelley A Donnelly*(74) Attorney, Agent, or Firm* — Banner & Witcoff, Ltd.(57) **CLAIM**

The ornamental design for a lap desk, as shown and described.

DESCRIPTION

FIG. 1 is a perspective view of a lap desk showing my new design;

FIG. 2 is a front view thereof, with the rear view being a mirror image thereof;

FIG. 3 is a right side view thereof, with the left side view being a mirror image thereof;

FIG. 4 is a top view thereof; and,

FIG. 5 is a bottom view thereof.

The broken lines in figures are for the purpose of illustrating portion of the lap desk and form no part of the claimed design.

1 Claim, 5 Drawing Sheets(56)
